ATTACHMENT FOR COMPARATORS

Robert O. Beardsley, Springfield, Vt., assignor to
 Jones & Lamson Machine Company, Springfield, Vt., a corporation of Vermont

Application May 9, 1935, Serial No. 20,564

4 Claims. (Cl. 88—24)

This invention relates to an illuminating attachment for comparators of the kind shown and described in the Hartness and Porter patent No. 1,703,933, issued March 5, 1929, or for the pedestal type of comparator shown and described in the Beardsley, Bysshe and Finn application Serial No. 747,200, filed October 6, 1934, for Comparators. In comparators of this type, a beam of light is usually projected across a portion of the periphery of the object to be tested, the magnified shadow image of this contour portion being thrown upon a screen where it can be compared with a standard diagram. Thus objects such as screw threads, gear teeth and the like, may be easily and accurately tested. In the case of other objects, such as type faces, punches, dies, etc., where it is desired to obtain an image of a surface portion, strong illumination of such surface is required as the image is formed by light reflected from the surface. According to the present invention, convenient means is provided for furnishing such illumination when desired. The illuminating means is adjustable so as to concentrate beams of light on the work when the latter is held in proper position in line with the optical axis of the lens system through which the image of the work is projected in magnified form on the screen, the light beams being arranged to fall on the surface of the work which is opposite the lens system. It is an object of the invention to provide illuminating means which can be readily moved out of the way into inoperative position when not wanted and may be readily moved back into operative position without disturbing any of the adjustments thereof. This illuminating means is thus available for use in supplementing the usual illuminating means by which a light beam is projected directly into the lens system across a portion of the contour of the work.

For a more complete understanding of the invention, reference may be had to the description of an embodiment thereof which follows, and to the drawings of which

Figure 1 is a side elevation of a pedestal type of comparator having an embodiment of the present invention attached thereto.

Figure 2 is a perspective view of one of the pivoted arms on which the illuminating units are supported.

Figure 3 is a perspective view of a stationary bracket on which the arm shown in Figure 2 is pivotally supported.

Figure 4 is a perspective view of one of the illuminating units.

Figure 5 is a fragmentary plan view of the comparator showing the illuminating units and their supports in operative position.

Figure 6 is a similar plan view showing the illuminating units in their inoperative position.

The comparator illustrated in Figure 1 includes a housing 10 which may be mounted on a suitable standard or pedestal 12. On the front side of the pedestal 12 are brackets 14 and 16 which act as guides for a vertical ram 18 on the upper end of which is an adjustable work table 20. This table may be raised or lowered by suitable means such as a hand wheel 22 which bears on the upper face of the bracket 14 and is screw-threaded on a portion 24 of the ram 18. The work table 20 is capable of various adjustments as described in application Serial No. 747,200, hereinbefore referred to. Projecting through the housing 10 is a magnifying lens system, the external portion of which is shown at 30. Work to be tested is mounted on the table 20 and is adjusted so that the portion of the work which is to be tested is aligned with the optical axis of the lens system 30. An image of this portion of the work is reflected by a mirror within the housing 10 onto a translucent screen as described in the afore-mentioned patent and application.

According to the present invention, a pair of illuminating units is mounted in such a way as to be capable of projecting beams of light against the portion of the work facing the lens system 30 so that a portion of the light is reflected into the lens system to form the image. As illumination of this sort is desired only for the testing of certain kinds of objects, the illuminating units are mounted so that they can be readily moved into and out of operative position without disturbing the adjustments thereof. As shown in Figure 4, each illuminating unit comprises a lamp house 32 enclosing a lamp (not shown), and a prism holder 34 on which is carried a reflecting prism 36. The lamp house is provided with a condensing lens mounted in a lens holder 38 which is directed toward the prism 36. The beam of light passing through the lens holder 38 to the prism 36 is internally reflected by the prism and emerges from the emergence face 40 of the prism, which, as shown, is preferably convex or is adjacent to a convex lens so as to concentrate the beam of light on the portion of the work which is in line with the optical axis of the lens system 30. The lamp, lamp house and prism holder are preferably constructed so as to be capable of various adjustments for the purpose of directing the light beam as desired. The lamp house

- and prism holder may be mounted, as shown in Figure 4, in spaced relation on a base or cross piece 44. This cross piece is in turn adjustably mounted on the free end of a pivoted arm 46. 5 To this end, the cross piece 44 may be provided with a central slot 48 through which a thumbscrew 50 passes for threaded engagement with the outer end of the arm 46. Thus the illuminating unit may be longitudinally or rotatably adjusted 10 with reference to the arm 46 and may be clamped in any desired position of adjustment by setting up on the thumbscrew 50. The arm 46 is provided with a pivot pin 52 adapted to rotate in a socket 53, the latter being supported by a stationary bracket 55 which may be secured to the housing 10 or to any other convenient stationary member associated therewith. As indicated in Figure 2, the arm 46 may be provided with a suitable lug 60 adapted to engage the bracket 55 to 15 limit the swing of the arm 46 when the illuminating unit is swung to its inoperative position as shown in Figure 6. The lug 60 is preferably formed in such a manner as to prevent contact between any portion of the illuminating unit and the housing 10, no matter what position of adjustment the illuminating unit may be with 20 reference to the arm 46. In order to determine the position of the arm 46 when the illuminating unit is in its operating position, an abutment screw 25 66 may be threaded through the arm 46 to engage a stationary lug 68 on the bracket 55. The screw 66 may be clamped in any position of adjustment as by a setscrew 70. The screw 66 thus makes it easy to move the arm 46 into correct 30 operative position. The arm may be held in this position or in any other position by a binding screw 72, which, when set up, clamps the pivot pin 52 in the socket 53.
- It is evident that various modifications and 35 changes may be made in the structure herein shown and described without departing from the spirit or scope of the invention defined in the following claims.
- I claim:—
- 40 1. In a comparator of the character described having a housing, a horizontal optical instrument projecting through said housing, and a work-supporting table in front of said housing; a hinged bracket mounted on said housing, an arm pivotally mounted on said bracket, a support member adjustably fixed at the free end of said arm, a 45 lamp house and a prism mounted in spaced relation on said support member, and means for adjustably limiting the angle of swing of said arm.
2. In a comparator of the character described including a horizontal optical instrument and 5 means for supporting work in line with the optical axis of said instrument; an illuminating unit swingable into and out of a predetermined adjustable position of operation, said unit comprising a lamp, a lamp house therefor, a prism, and a prism holder in spaced relation to said lamp house, and means for supporting said illuminating unit, said supporting means including an arm swingable in a horizontal plane, a cross piece adjustably mounted on said arm, a lamp house and 10 prism holder being mounted on said cross piece.
3. In a comparator of the character described including an optical instrument, means for supporting said instrument, and an adjustable table for holding the work in line with the optical axis 15 of said instrument; a pair of hinged brackets pivotally mounted in said supporting means, a cross piece adjustably mounted on the free end of said bracket, a lamp house and a prism holder mounted on each said cross piece, a lamp in each 20 lamp house, a prism in each prism holder, and means on each said bracket for limiting the pivotal motion thereof to one extreme position in which the lamp and prism are in operative position relative to the work, and to an inoperative 25 position wherein the lamp house and prism holder are held in said supporting means.
4. In a comparator of the character described including a housing, an optical instrument projecting through said housing, and a table adjustable to support the work in line with the optical axis of said instrument; a pair of hinged brackets pivotally mounted on said housing, an illuminating unit adjustably mounted on each 30 said bracket to swing into and out of operative 35 position without change of adjustment, each said unit comprising a cross piece adjustably supported on its bracket, a lamp house and a prism holder mounted on the cross piece in spaced relation to each other, a lamp in said lamp house, and prism in said holder, stop means for limiting the extreme positions of each said bracket, one of said extreme positions being the operative 40 position, and means for clamping each said bracket in either extreme position.
- 50

ROBERT O. BEARDSLEY.
